US00D664087S

(12) **United States Design Patent**
Chin-Ho Kim et al.

(10) **Patent No.:** US D664,087 S
(45) **Date of Patent:** ** Jul. 24, 2012

(54) **COLUMN OF AN ELECTRIC VEHICLE CHARGING STATION**

(75) Inventors: **Darren Chin-Ho Kim**, Oakland, CA (US); **David Baxter**, Monte Sereno, CA (US); **Craig T. Matsuno**, San Jose, CA (US); **Price Terzis**, Los Altos Hills, CA (US); **Peter H. Muller**, Woodside, CA (US)

(73) Assignee: **Coulomb Technologies, Inc.**, Campbell, CA (US)

(**) Term: **14 Years**

(21) Appl. No.: **29/397,169**

(22) Filed: **Jul. 12, 2011**

(51) LOC (9) Cl. **13-02**

(52) U.S. Cl. **D13/107**

(58) **Field of Classification Search** D13/106–110, D13/118–119, 184, 199; D15/9; 320/103–115

(57) **CLAIM**

The ornamental design for a column of an electric vehicle charging station, as shown and described.

DESCRIPTION

FIG. 1 shows a perspective view of a column of an electric vehicle charging station;

FIG. 2 shows a front view of the column of the electric vehicle charging station of FIG. 1;

FIG. 3 shows a back view of the column of the electric vehicle charging station of FIG. 1;

FIG. 4 shows a left view of the column of the electric vehicle charging station of FIG. 1;

FIG. 5 shows a right view of the column of the electric vehicle charging station of FIG. 1;

FIG. 6 shows a top view of the column of the electric vehicle charging station of FIG. 1;

FIG. 7 shows a bottom view of the column of the electric vehicle charging station of FIG. 1; and,

FIG. 8 shows a detailed view of the body of the column of the electric vehicle charging station of FIG. 1.

The broken lines illustrate environmental structure and form no part of the claimed design.
